[57] **ABSTRACT**

A knitting machine equipped with two-part needles each having a latchless hooked element and a relatively slidable loop-controlling element having a loop retaining shoulder and a point for closing the hook. The hooked element has only one operating butt co-operable with cams of a single cam track. The two elements have abutments for contact with one another to effect movements of the elements together in both directions. Provision is made for lost motion between the elements. The stem of the loop-controlling element of each needle is formed for engagement with means in the machine for holding or restricting movements of the loop-controlling elements at required times.

FIG. 12.

IMPROVED KNITTING MACHINE EQUIPPED WITH TWO PART NEEDLES

This invention relates to a knitting machine needle, and has reference particularly to a two-part needle of a previously proposed form comprising (a) an individually slideable and latchless hooked element having an open yarn-receiving and drawing hook at its upper or outer extremity, and (b) an independently and relatively slideable loop-controlling element operable in front of the hooked element and having at its upper or outer extremity an old loop retaining shoulder and an adjoining point adapted to close the hook each time the needle is retracted to draw a new loop through a retained old loop and the latter is cast-off the needle at a knocking-over point. Such a needle will be hereinafter referred to as a two-part knitting machine needle "of the form herein referred to".

Accordingly, the hook-closing point of the loop-controlling element of a two-part knitting machine needle of the form herein referred to takes the place of the pivoted latch of a conventional needle of the latch type. Hence, such a two-part needle overcomes the disadvantages of a conventional latch needle with its inherent latch weakness and its liability to failure in modern high speed multi-feed machines.

Moreover, since the hooked element of a two-part needle of the form herein referred to is only called upon to make relatively small rectilinear movements, in contradistinction to a conventional latch needle to the latch of which requires to swing right open through approximately 180° before the advancing needle reaches its clearing position, the cam lifting heights for operating a two-part needle of the aforesaid form can be reduced by as much as from 25 percent to 30 percent. This, in turn, reduces cam lengths and makes possible an increase in the number of feeds in the machine. Added to this, two-part needles of the described form impose less wear on cams, needle butts and the needle bed tricks because smoother forms of cam tracking are possible with shallower cam rises.

With a two-part needle of the herein referred to form in operation, the hooked element and the associated loop-controlling element in front thereof are sometimes required to slide together and at other times there is relative sliding movement between the two. That is to say, whenever the hooked element is advanced from its fully retracted position to its intermediate advanced, i.e., tucking position, it does so relatively to the loop-controlling element which is held stationary or substantially so. But when the hooked element is advanced beyond the tucking position, the loop-controlling element is also advanced to a small extent so that the old loop becomes retained on the shoulder and positioned around the point. However, as the hooked element commences its subsequent retraction to draw a new loop through the retained old loop on the point, the loop-controlling element is again held stationary or substantially so until, in fact, the hook is covered and thereby closed by the point. Therefore, both elements are retracted together sufficiently far to enable the old loop to be cast-off the needle at the knocking-over position.

Heretofore, these various sliding movements of the said two elements in their trick in the needle bed, both together and relatively, have been effected by cams of separate cam tracks which have respectively been ar-

ranged to act upon two separate operating butts — one on the stem of the hooked element and the other on the stem of the associated loop-controlling element. Naturally, the provision of two operating butts on each two-part needle and of two corresponding needle-operating cam tracks has complicated a knitting machine equipped with such needles.

The primary object of the present invention is to provide a generally improved two-part needle of the form herein referred to which is adapted to be operated by cams in a single cam track.

Another object is to provide, in a knitting machine equipped with the improved two-part needles, simple and effective means for exercising control over the yarn-controlling elements of those needles.

According to this invention, the hooked element only of the improved needle is furnished with an operating butt, this butt being co-operable with cams of a single cam track for effecting the required rectilinear advancing and retracting movements of the hooked element, the sliding movements of the loop-controlling element together with the hooked element in both directions being effected by mutual contact between abutments respectively provided on the two elements, there being provision for lost motion between the two elements to permit of the required sliding movements of the hooked element relatively to the loop-controlling element, and the stem of the latter being formed for engagement with means of any suitable character in a knitting machine to hold or restrict movement of the loop-controlling element at required times.

The abutments on the two elements arranged to come into contact with one another whenever the loop-controlling element is required to be advanced by and together with the hooked element may advantageously consist of a relevant edge of the aforesaid operating button of the hooked element and the opposed extremity of the tail portion of the stem of the loop-controlling element.

On the other hand, the abutments on the two elements arranged to come into contact with one another whenever the loop-controlling element is required to be retracted by and together with the hooked element, may conveniently consist of a relevant edge of a frontal projection on the stem of the hooked element and an opposed shoulder on the loop-controlling element constituted by one end of a recess formed on the back of the stem of the last mentioned element.

The aforementioned lost motion between the two elements is achieved by the provision of the recess in the back of the loop-controlling element and the extent of the lost motion is determined by the length of this recess.

Although the improved two-part needle of this invention is, as already described, furnished with only one principal operating butt which is, in effect, common to both of the elements of the needle, the latter may, of course, be provided with any required number of additional butts, e.g., for selection purposes and knitting variations.

The improved needle, moreover, is applicable to circular knitting machines, both plain and rib, as well as to flat bed knitting machines — of all appropriate types.

As to the means in a knitting machine for holding, i.e., restricting rectilinear sliding movements of, the loop-controlling elements at required times, such

means may take any appropriate one of various forms.

For example, in the case where improved two-part needles of this invention are mounted in a needle cylinder yieldable and over-ridable latching means comprising a spring retaining band which embraces the cylinder and is engageable in recesses in the stems of the loop-controlling elements may be employed. Alternatively, the loop-controlling elements may themselves be made yieldable, e.g., by the provision in their back edges of suitable reliefs, and be formed on the front edges of their stems with lobes for engagement in either one or the other of two grooves formed in a fixed control ring of sectional form surrounding the needle cylinder.

A somewhat similar arrangement to that last mentioned may be adopted in conjunction with a needle dial of a circular rib machine, the only difference being that in this case the fixed grooved ring would be annularly grooved in the plane of the dial.

Again, in the case of a flat needle plate or bed in a flat knitting machine, either a straight spring member, engageable in recesses in the stems of the loop-controlling elements may be provided, or a straight suitably grooved fixed bar may be arranged in association with the bed for co-operation with protuberances on yieldable loop-controlling elements.

But, in yet another possible arrangement, applicable more especially to a flat needle bed or a needle dial (but also applicable to a needle cylinder), the loop-controlling elements may be formed for engagement with movement-restricting stops, abutments, plates, cam portions or the like fitted in suitable positions to the cam plate, the dial cam cap or the cylinder cam box, as the case may be. The idea in this further arrangement is that, by virtue of the relative movement between the needle bed and the cam plate the dial cam cap or the cylinder cam box, as the case may be, the loop-controlling elements of the two-part needles at the relevant times either strike, or are struck by, the stops, abutments, plates, cam portions or the like and are thereby temporarily held; i.e., restricted in their sliding movements, and at all other times are clear of the restricting parts so as to be free for movements together with the associated hooked elements. But in this further arrangement, the provision of a retaining bar or ring is necessary to hold the loop-containing elements in in their tricks in front of the hooked elements.

Yet again, the loop-controlling elements may, if desired, be frictionally held in their tricks and thereby restricted from movement until such times as they are forcibly moved against the frictional influence by virtue of being contacted by projections or butts on the corresponding hooked elements. For instance, the stem of each loop-controlling element may be laterally bowed or crimped suchwise as to produce friction between it and the opposite side walls of its trick. In this variation, a flat retaining bar, or ring, according to the form of the needle bed employed, is provided to retain the loop-controlling elements in the bed.

A still further possibility is for loop-controlling elements, retained in the needle bed by a retaining bar or ring, to be prevented from sliding movements in their tricks at appropriate times by a restrictor bar or ring which is cut away both at the places where the associated hooked elements are advanced to clearing positions and also at the old loop-knocking-over positions

where the hooked elements and the loop-controlling elements are retracted together.

Where, as may be, the hooked element of the improved needle is formed with a swell portion adjacent to the hook, this portion may advantageously be grooved for reception and guidance of the loop-controlling element. But such a groove may not be essential in which case it can be eliminated.

In order that the invention may be more clearly understood and readily carried into practical effect, specific constructional examples thereof will now be described with reference to the accompanying drawings, wherein,

FIG. 1 is a vertical sectional view of a needle cylinder and its cam box, showing a two-part needle fully retracted, this needle functioning in conjunction with a yieldable and over-ridable latching means including a simple spring retaining band,

FIGS. 2, 3 and 4 are three similar views but with the needle shown at respectively different stages during a knitting cycle,

FIG. 5 is a detail vertical sectional view showing a modification,

FIG. 6 illustrates the single cam track for operating and controlling the two-part needle illustrated in FIGS. 1 - 4,

FIG. 7 is a view similar to FIG. 1 illustrating an example of the modification in which the loop-controlling elements are yieldable for co-operation with a grooved ring,

FIG. 8 is another similar view depicting an arrangement wherein the loop-controlling elements are formed for engagement with movement-restricting abutments or cams,

FIG. 9 illustrates a section of the cylinder cam system suitable for controlling two-part needles as depicted in FIG. 8,

FIG. 10 is a still further view similar to FIG. 1 showing a variation in which the loop-controlling elements are frictionally held in their tricks,

FIG. 11 comprises an edge view of one of such loop-controlling elements and also a fragmentary elevational view of the tricked face of a needle cylinder showing a frictionally held loop-controlling element accommodated in one of the tricks, and

FIG. 12 is a detail view hereinafter to be described,

FIG. 13 is a detailed view similar to FIG. 12 but showing the portions in perspective view for greater clarity.

Referring to FIG. 1, the numeral 1 indicates a section of an annular cam box with a cam track 2, and 3 indicates a needle cylinder. The numerals 4 and 6 respectively indicate the hooked element and the loop-controlling element of a two-part needle according to this invention. On the front of the stem of the hooked element 4 is provided a rectangularly shaped projection 7 arranged in an elongated recess 6a formed on the back of the stem of the loop-controlling element 6. The upper and lower ends of this recess define shoulders on the element 6. In conjunction with the loop-controlling elements 6 there are provided yieldable and overridable latching means which include a spring retaining band 8 which completely embraces the cylinder 3 and is engageable in one or the other of two recesses 6b and 6c formed in the front or outer edge of the stem of the loop-controlling element 6, there being a protuberance

6d on the stem between those two recesses so as to define and separate the same. The recess **6b** in the stem of each loop-controlling element **6** nearest to a bevelled point **13** of the latter is for holding the said element stationary or substantially so whenever the corresponding hooked element **4** is relatively advanced to its intermediate tucking position, whereas the other recess **6c** farthest from the point is for holding the loop-controlling element **6** whenever the hooked element **4** commences its subsequent retraction to draw a new loop and until the hook **4a** is closed by the point **13**.

The recess **6c** farthest from the point **13** of the loop-controlling element **6** is just of a sufficient dimension, lengthwise of the said element, as to hold the latter stationary relatively to the hooked element **4** whenever the spring retaining band **8** is engaged in this particular recess. On the other hand, the recess **6b** nearest to the point **13** is elongated somewhat and made of such length as to enable the two elements **4** and **6** of the needle to be retracted together a variable distance depending on the precise desired length of the new loop being drawn, in accordance with the quality setting of the stitch cam.

In any event, the functioning of the yieldable latching means just described is such that whenever the hooked element **4** is advanced beyond its tucking position and the two elements of the needle move together, the spring band **8** will be over-ridden, i.e., acted upon and caused to yield by the protuberance **6d** between the two recesses whereby it is forcibly displaced from the elongated recess **6b** and thereupon permitted to spring into the companion short recess **6c**. Conversely, whenever the two elements **4** and **6** are retracted together, the spring retaining band **8** will again be acted upon and caused to yield by the protuberance **6d** so that the band will be displaced from the short recess **6c** farthest from the point **13** and permitted to spring into the elongated recess **6b** nearest to the said point.

Immediately beneath its hook **4a** the element **4** is formed with a swell which, as shown most clearly in FIG. 12, is grooved at **9** to receive and guide the upper portion of the element **6**.

In FIG. 1 the two-part needle has just drawn a new loop **5**, the old loop having been cast off the needle. The elements **4** and **6** have just been retracted together, the band **8** is in the longer one **6b** of the two recesses **6b** and **6c** and the upper edge **11a** of a single operating butt **11** on the hooked element **4** is below and clear of an edge **10** at the lower extremity of the element **6**.

In FIG. 2 the hooked element **4** has been advanced, i.e., raised, to its intermediate tucking height above the cylinder verge, the loop-controlling element **6** being meantime restrained from upward movement by engagement of the band **8** with the protuberance **6d** at the lower end of the recess **6b** until the tail edge **10** of the element **6** is contacted by the upper edge **11a** of the butt **11**. At this stage, moreover, the upper edge **7a** of the projection **7** on the element **4** is in contact with the shoulder at the upper end of the recess **6a**.

In FIG. 3 the hooked element **4** has been fully advanced, with the old loop **12** positioned over or around the point **13** and supported upon the old loop retaining shoulders **rs** of the loop-controlling element **6** and a yarn **14**, fed by a suitable feeder or guide, being taken into the hook **4a**. The old loop retaining shoulder **rs** is more clearly shown in FIGS. 5 and 12.

Referring to FIG. 4, it will be seen that the loop-controlling element **6** is held by the spring band **8** (at this stage engaged in the recess **6b**) while the hooked element **4** is being retracted with the yarn **14** in its hook **4a**. It is to be noted that at this stage the hook is covered, and thus closed, by the point **13**. The rectangular projection **7** on the element **4** is now in contact with a shoulder **15** defined by the lower end of the recess **6a** in the loop-controlling element **6**, so that both of the elements **4** and **6** will be retracted, i.e., lowered, together during the drawing of a new loop **12¹** of the yarn **14** through the loop **12**.

FIG. 5 illustrates a variation in which a groove in the swell immediately beneath the hook **4a** of the hooked element **4** is eliminated.

As to the single cam track illustrated in FIG. 6, this incorporates a swing cam **16** which is adapted to be set in one of two positions, viz., either the position shown to raise the hooked elements **4** to full knitting or clearing height, or a lower position to raise the hooked elements to tucking height only. Alternatively, solid fixed cams (not shown) for knitting or tucking may be employed. In another arrangement, conventional jack lifting cam such as **18** (for knitting, or tucking) may be provided for use in conjunction with normal pattern selection devices.

Referring to FIG. 7, the back edge of the stem of each of the loop-controlling elements **6** is relieved at **6e** to enable it to yield radially inwards whenever a rounded lobe **19** on the front edge of the said stem is acted upon by a protuberant annular rib **20** on a sectional grooved ring **21** which surrounds the needle cylinder **3** and is mounted on top of the cam box **1**. The ring **21** has formed in its annular face two superimposed movement-restricting grooves **22** and **23** separated by the rib **20**. The lobe **19** on each element **6** engages in one or the other of the two grooves.

In the variation shown in FIGS. 8 and 9, the front edge of the stem of each element **6** is formed with a triangular-shaped butt **24** for contact with either the lower upwardly bevelled edges (during advance of the hooked element **4**) or the upper downwardly bevelled edges (during retraction of the element **4**) of movement-restricting abutments or cam formations such as **25** provided on a sectional ring **26**. This ring, like the ring **21** in FIG. 7, surrounds the needle cylinder **3** and is mounted on top of the cam box **1**. Moreover, the ring **26**, also like the ring **21**, serves to hold the loop-controlling elements **6** back against the front edges of the hooked elements **4**. As will be appreciated, both of the elements **4** and **6** of a two-part needle are permitted to move together whenever they pass through gaps **27** (see FIG. 9) between the abutments or cam formations **25**.

In FIG. 10 is shown, in side elevation, a loop-controlling element **6** which, as seen in FIG. 11 from the outside of the needle cylinder **3**, is longitudinally bowed from end to end. Thus, when accommodated in its trick **28**, the opposite sides of each element **6** make efficient frictional contact with the respectively opposite side walls of the trick **28**. In this way, the element **6** is frictionally held and can only be positively moved against the movement-restricting frictional influence by contact with the hooked element **4** at appropriate stages of the cam-controlled raising and lowering movements thereof. In the FIG. 10 variation a ring **26**

is provided to hold the elements 6 back against the front edges of the companion elements 4.

FIGS. 12 and 13 shows more clearly than any of the other figures the swell 29 of the hooked element 4, which swell is grooved at 9 to receive and guide the upper end portion, i.e., the suitably bevelled point 13, of the loop-controlling element 6. FIGS. 12 and 13 also shows that this point 13 and the adjoining upper portion of the said element is reduced somewhat in thickness at 30 to enable it to be slidably engaged within the groove 9. Alternatively, the upper region of the element 6 may be of tapered cross-section at 30 to co-operate with a vee groove in the swell 29.

We claim:

1. A knitting machine including a tricked needle bed and, mounted in tricks in said bed, two-part knitting needles each comprising (a) an individually slidable and latchless hooked element having an open yarn receiving and drawing hook and (b) an independently and relatively slidable loop-controlling element operable in front of the hooked element and having an old loop retaining shoulder and an adjoining point adapted to contact or cover the hook each time the needle is retracted to draw a new loop through a retained old loop and the latter is cast off the needle at a knocking-over point: wherein the improvement resides in the provision on the hooked element of each two-part needle of only one operating butt which is co-operable with cams of a single cam track for effecting required rectilinear advancing and retracting movements of the said hooked element; and in that the sliding movements of the loop-controlling element together with the hooked element of each needle in both directions are effected by mutual contact between abutments on the two elements; provision being made for lost motion between the said two elements to permit the required sliding movements of the hooked element relatively to the loop-controlling element, said loop-controlling element and a portion of the machine adjacent the loop-controlling element constituting, respectively, first and second cooperating parts, and including restricting means for restricting rectilinear movement of the loop-controlling element relative to the machine, said restricting means including at least two recesses, both of which are on one of said cooperating parts, said recesses separated by a protuberance, and a projection on the other of said cooperating parts, said projection projecting into either of said recesses, said projection arranged to override the protuberance to move to either of said recesses.

2. A knitting machine according to claim 1, wherein abutments on the two elements of each two-part needle arranged to come into contact with one another whenever the loop-controlling element is required to be advanced by and together with the hooked element consists of an edge of the operating button the hooked element and the opposed extremity of a tail portion of the stem of the loop-controlling element.

3. A knitting machine according to claim 1, wherein abutments on the two elements of each two-part needle arranged to come into contact with one another whenever the loop-controlling element is required to be retracted by and together with the hooked element consists of a relevant edge of a frontal projection on the stem of the hooked element and an opposed shoulder on the loop-controlling element constituted by an end

of a recess formed in the back of the stem of the last mentioned element.

4. A knitting machine according to claim 3, wherein the said recess formed in the back edge of the stem of the loop-controlling element of each two-part knitting needle provides lost motion between the two elements of the needle, the extent of this lost motion being determined by the length of said recess.

5. A knitting machine according to claim 1, wherein 10 said restricting means includes a yieldable and over-ridable member which yieldingly contacts the needle bed and is engageable in recesses in the stems of said loop-controlling elements.

6. A knitting machine according to claim 1, said re- 15 stricting means including the construction wherein the loop-controlling element of each two-part knitting needle is made yieldable by providing a relief in its back edge and is formed on the front edge of its stem with a projection in the form of a single lobe for engagement 20 in either one or the other of said recesses in the form of two grooves formed in a fixed control component located adjacent to the needle bed.

7. A knitting machine according to claim 1, said re- 25 stricting means including the construction wherein the loop-controlling elements of the two-part knitting needles are formed for engagement with movement-restricting formations on a restrictor component which serves to hold the said loop-controlling elements into their tricks in front of the hooked elements.

8. A knitting machine according to claim 5, wherein 30 there are formed in the front edge of the stem of the loop-controlling element of each two-part knitting needle two recesses which are defined and separated by an intermediate protuberance on the stem, the recess nearest to the point of the loop-controlling element being adapted to co-operate with the spring retaining member to hold the said element substantially stationary whenever the corresponding hooked element is relatively advanced to an intermediate tucking position, 40 whereas the other recess farthest from the said point is for holding the loop-controlling element whenever the hooked element commences its subsequent retraction to draw a new loop and until the hook is contacted or covered by the point, the spring retaining member being acted upon and caused to yield by the protuberance so that the member is displaced from the relevant recess and permitted to spring into the other recess whenever the two elements are caused to move together in either of said advancing and retracting direc- 50 tion.

9. A knitting machine according to claim 8, wherein 55 the recess farthest from the point is of just sufficient dimension, lengthwise of the loop-controlling element, as to hold the latter stationary relatively to the hooked element whenever the spring retaining member is engaged in this particular recess, whereas the recess nearest to the point is elongated and of such length as to enable the two elements to be retracted together a variable distance depending on the desired length of the new loop being drawn.

10. A knitting machine according to claim 1, wherein 60 the hooked element of each two-part knitting needle is formed adjacent to its hook with a swell portion which is grooved for reception and guidance of the loop-controlling element.

11. A knitting machine according to claim 10, wherein the point and the adjoining upper portion of

the loop-controlling element is reduced in thickness to enable it to be slidably engaged within the groove in the swell portion of the hooked element.

12. A knitting machine according to claim 5 which is of the circular type and wherein the spring retaining member is in the form of a band embracing a tricked needle cylinder in which the two-part knitting needles are mounted.

13. A knitting machine according to claim 6, which is of the circular type and wherein the two-part knitting needles are mounted in a tricked needle cylinder, the single lobe on the front edge of the stem of the loop-controlling element of each needle being rounded and arranged to be acted upon by a protuberant annular rib on a sectional ring which surrounds the needle cylinder and has formed in its annular face two movement-restricting grooves separated by the said rib and in one or the other of which the said lobe engages.

14. A knitting machine according to claim 1 which is of the circular type and has a tricked needle cylinder wherein the two-part knitting needles are mounted therefore.

15. A knitting machine including a tricked needle bed and, mounted in tricks in said bed, two-part knitting needles each comprising (a) an individually slideable and latchless hooked element having an open yarn receiving and drawing hook and (b) an independently and relatively slideable loop-controlling element operable in front of the hooked element and having an old loop retaining shoulder and an adjoining point adapted to contact or cover the hook each time the needle is re-

tracted to draw a new loop through a retained old loop and the latter is cast off the needle and a knocking-over point: wherein the improvement resides in the provision on the hooked element of each two-part needle of only one operating butt which is co-operable with cams of a single cam track for effecting required rectilinear advancing and retracting movements of the said hooked element; and in that the sliding movements of the loop-controlling element together with the hooked element of each needle in both directions are effected by mutual contact between abutments on the two elements; provision being made for lost motion between the said two elements to permit the required sliding movements of the hooked element relatively to the loop-controlling element, and the stem of the latter being formed for engagement with means in the machine for holding or restricting movement of the said loop-controlling element at required times,

and wherein the front edge of the loop-controlling element of each such needle is formed with a triangular butt for contact with either the lower upwardly bevelled edges or the upper downwardly bevelled edges of movement-restricting abutments on a sectional ring surrounding the said needle cylinder, this ring serving to hold the loop-controlling elements back against the front edges of the hooked elements and both of the elements of each needle being permitted to move together whenever they pass through gaps between the said abutments.

* * * * *
